TELEPHONE TRANSMITTER SUPPORT
AND SILENCER

Albert C. Reinhold, Marietta, Pa.

Application April 15, 1947, Serial No. 741,614

5 Claims. (Cl. 179—180)

1

The present invention relates to telephony and more particularly to a novel transmitter support.

In telephone instruments as now in general use, the transmitter is open for conversation as soon as removed from the hook or hand set and the only way to prevent sounds from being transmitted is to hold one's hand over the mouthpiece. It is a common occurrence for the user of the telephone to lay the instrument on the desk while using the hands to sort out papers or obtain other information, and therefore the transmitter is open to receive side talk not intended for the person at the receiving end of the line. This is highly undesirable, as often information is transmitted thoughtlessly by the user who for the moment overlooks the fact that the transmitter is subject to conversation in proximity to the instrument.

Some of the objects of the present invention are; to provide a novel sound cut-off valve for telephone transmitters; to provide a supporting holder for a telephone instrument which serves to prevent extraneous conversation and noise being transmitted when the instrument is removed from the hook or hand set; to provide a supporting holder for sealing the mouthpiece of a telephone transmitter whenever the instrument is placed on a desk or table so that the hands of the user are free; to provide a novel silencer for telephone transmitters whereby only legitimate conversation will be transmitted to the person at the receiving end of the line; and to provide other improvements as will hereinafter appear.

In the accompanying drawings, Fig. 1 represents a plan of a telephone transmitter closure valve embodying one form of the present invention; Fig. 2 represents a bottom plan of the same; Fig. 3 represents a side elevation of a telephone instrument showing the closure valve in operative position; Fig. 4 represents a plan of a closure valve embodying a modified form of the invention; Fig. 5 represents a bottom plan of the modification of Fig. 4; and Fig. 6 represents a side elevation of the modification of Fig. 4.

Referring to the drawing, one form of the present invention comprises a valve disc 10 having a diameter greater than the transmitter unit 11 of the type of telephone instrument 12 having the receiving unit 13 at its other end. The face of the disc 10 is provided with four upstanding stops 14 so spaced apart in pairs as to precisely locate the face of the telephone transmitter within the boundary of the disc 10 in any one of the four positions determined by the spaced stops 14.

2

In order that the valve disc 10 seals the mouth of the transmitter 11, the face of the disc 10 opposite to the face having the stops 14 is provided with pairs of radially disposed anti-rock lugs 15, each pair of such lugs 15 being so arranged that whichever pair of stops 14 is engaged by the transmitter, the lugs 15 will counteract any tendency of the valve disc to tilt about the particular disc diameter used by the transmitter.

As a means to form a fulcrum to permit the valve disc 10 to rock to the required angle defined by the face of the transmitter, a coaxially located ring 16 is attached to the bottom face 15 of the disc 10, such ring 16 having a diameter related to the diameter of the disc so that when rocked to transmitter-supporting position the upper face of the disc 10 will fit tightly against the transmitter face as a seal to prevent any sound from reaching the transmitter. As shown, the ring 16 is preferably as a part of the face of the disc to provide a through hole covered by a magnifying lens, so that the disc may be used for reading or examination purposes.

25 In the form of the invention shown in Figs. 4 and 5, the valve unit is a one position unit, comprising a segmental disc 17 having a straight edge 18 forming a support for the disc when rocked to operative position with a telephone transmitter 20 in place. For holding the transmitter an arcuate rest 20 is provided and supported at its end by two fixed stops 19. The radius of the rest 20 is the same as that of a telephone transmitter so that the latter fits snugly in place.

35 For supporting the disc 17, the bottom face thereof is provided with two parallel, flat elongated legs 21, each having a horizontal edge 22 and an edge 23 inclined towards the edge 18. Thus, when the valve rests upon the two edges 22 40 it is substantially horizontal, ready to receive a transmitter, and when the latter is placed thereon the disc rocks rearwardly upon the edges 23 to reach a stable position resting upon the edge 18 as well. Coaxially of the disc 17 there is a 45 through hole 24 closed by a magnifying lens 25.

Having thus described my invention, I claim:

1. As a new article of manufacture, a disc valve, means upon one face thereof to fit said valve over the mouthpiece of a telephone instrument, and means on the opposite face of said disc forming a support for holding said valve in closed position when a telephone instrument rests in part on said disc and in part on the surface supporting said disc.

55 2. As a new article of manufacture, a disc valve, means upon one face thereof to fit said valve over

the mouthpiece of a telephone instrument, means on the opposite face of said disc forming a support for holding of said valve in closed position when a telephone instrument rests in part upon said disc and in part on the surface supporting said disc, and means on said disc to prevent lateral rocking of said support relative to the longitudinal axis of said instrument.

3. A silencer holder for telephone instruments having a receiver at one end and a transmitter mouthpiece at the other end, comprising a disc valve to rest upon a horizontal surface and be fitted against said mouthpiece to shut off ambient sound, means adapted to tilt said valve under the weight of said mouthpiece to seal said mouthpiece, and means coacting with said tilting means to form a stable support for said valve in tilted position while said receiver rests upon the same horizontal surface.

4. A silencer holder for telephone instruments having a receiver at one end and a transmitter mouthpiece at the other end comprising a disc valve to rest upon a horizontal surface and be fitted against said mouthpiece to shut off ambient sound, a coaxially located ring projecting from the bottom of said disc adapted to tilt said disc under the weight of the superposed mouthpiece, and spaced lugs functioning with said ring as a stable support to hold said valve in closed position.

5. A silencer holder for telephone instruments

having a receiver at one end and a transmitter mouthpiece at the other end comprising a disc valve to rest upon a horizontal surface and be fitted against said mouthpiece to shut off ambient sound, a coaxially located ring projecting from the bottom of said disc adapted to tilt said disc under the weight of the superposed mouthpiece, spaced lugs functioning with said ring as a stable support to hold said valve in closed position, and spaced stops on the valve face to maintain said mouthpiece centered.
